Baribeau & Fils Inc., Levis, Quebec, Canada

Filed Sept. 5, 1972, Ser. No. 286,186

Term of patent 14 years

Int. Cl. D7—04

U.S. Cl. D7—46

FIG. 1 is an end elevation of a combined carving board and meat holder, showing my new design.

FIG. 2 is a top plan view;

FIG. 3 is an elevation of one side;

FIG. 4 is an elevation of the opposite side; and

FIG. 5 is a fragmentary perspective view showing the end opposite that of FIG. 1 to an enlarged scale.

The end opposite the end shown in FIG. 1 is as in FIG. 1. The bottom is plain and unornamented.

I claim:

The ornamental design for a combined carving board and meat holder, as shown and described.
